UNITED STATES PATENT OFFICE

ORESTES PAGAN, OF PHILADELPHIA, PENNSYLVANIA.

CAR-AXLE BOX.

SPECIFICATION forming part of Letters Patent No. 287,572, dated October 30, 1883.

Application filed November 13, 1882. (No model.)

To all whom it may concern:

Be it known that I, ORESTES PAGAN, a citizen of the United States, residing at Philadelphia, in the county of Philadelphia and State 5 of Pennsylvania, have invented certain new and useful Improvements in Car-Axle Boxes, of which the following is a specification, reference being had therein to the accompanying drawings, wherein—

10 Figure 1 is a vertical longitudinal section of a car-axle box embodying my invention. Fig. 2 is a side elevation. Fig. 3 is a similar view of the inner section of the box. Fig. 4 is an end view of the box and section on line 2 2, Fig. 1. Fig. 5 is a central section on line 11, Fig. 1. Fig. 6 is a broken perspective of box. Fig. 7 is a detail perspective of journal brass 20 bearing. Fig. 8 is a section of axle-journal through line 3 3, Fig. 9, the attached collar being in elevation. Fig. 9 is an elevation of axle-journal with collar attached thereto. Fig. 10 is a perspective of a modified form of axle-box embodying my improvements. Fig. 11 is a perspective of axle-box lid, and Fig. 12 is a 25 longitudinal vertical section of same.

My invention has relation to car-axle boxes, and has for its object to exclude dust and dirt from the box; to oil the journal and bearing without using packing on the back of the box, 30 waste-pumps, chains, or other like appliances; to prevent breakage or undue wear of the box or its parts by the end-thrust of the axle, and to provide a spring catch or lock for the axle-box lid, to the accomplishment of which my 35 invention accordingly consists of, first, the provision of a collar permanently secured to the axle, which has an annular groove or chamber in its forward or outer face, and subserves the purposes of a dust-excluder and oiling device, and prevents the end-thrust of the axle; 40 second, to the provision of a car-axle box made in two sections, the inner one of which contains the oil-bearing for the journal, and to which is attached the box-lid; third, to the 45 provision of a box, a collar on the axle, and an interposed packing or gasket between the front face of the collar and the axle-box; fourth, to the provision of a lid having a spring catch or lock, as hereinafter more specifically 50 described, whereby the lid is automatically locked or secured in its normal position on the

box to close the same, and may be readily unfastened to obtain access thereto, and, fifth, to the novel combination, construction, and arrangement of parts, as hereinafter more particularly described and claimed.

Referring to the accompanying drawings, A represents an axle-box composed of inner and outer sections, B and C, respectively. The section B has open front and rear ends, b b' , a seat, b^2 , for the journal-bearing, an oil-well, b^4 , external flanges, b^5 b^6 , and is formed with grooves b^7 on opposite sides, as shown. The flange b^8 is set back to any desired distance from the rear end of the section B to form a seat, b^9 , for the reception of a gasket or packing, D, as plainly illustrated in Fig. 1. The section B is circular in transverse section, as indicated in Fig. 5, in order that the seat b^9 may be of a corresponding configuration suitable to receive said gasket or packing-ring. The section C has an open top and a front end, c , with inwardly-projecting ribs or flanges, c^1 c^2 , a rear end, c^3 , recessed or cut away at c^4 , and a bottom, c^5 . Upon the axle E is permanently secured thereto a collar, F, which is provided with an annular chamber or recess, f , in its forward side or face f' . Said collar may be keyed or screwed to the axle; but I prefer to either shrink it thereon or secure it in its position by means of hydraulic or other pressure in a manner similar to that practiced for attaching car-wheels to the axles. The latter so provided are, with their brasses or bearings G, inserted into the section B 85 until the edge or face f' of the collar F abuts against the packing-ring or gasket D, as shown in Fig. 3. The key H is then inserted to secure the bearing G in position, whereupon the section C is slid onto section B, the ribs or flanges c^1 c^2 entering the grooves b^7 of section B, as more plainly shown in Figs. 6 and 10. Said sections are thereby held in due relation with each other to form the box A, the collar F being between the end of section B and the rear wall of section C, as shown in Fig. 1, the result whereof is that the rear of the axle-box is completely closed, so that no dust can obtain access thereto when said parts are placed in position as described. A flap, I, hinged 100 to i to section B, is turned down to fill up the recess or cut-away part c^4 of the rear end of

section C. The latter may be formed with lugs J J or ribs K K, for attachment of the box to the truck or equalizing-bar thereof. When the ribs K K are used, the sections B and C 5 are secured together by means of screws or bolts k k, as plainly shown in Fig. 10. The oil for the bearing and journal is placed or poured into the section B, from whence it flows to the chamber or annular recess in collar F, 10 and as the latter revolves with the axle the oil is carried up by said collar and falls upon the end g of bearing G. To provide for the proper lubrication of the journal, the bearing G is recessed at g', and provided with openings g'', as shown in Figs. 1 and 7, so that as the oil from the collar F flows on the end g of said bearing it passes to the recess g', and thence through the openings g'' to the journal. 15 If desired, the collar F may be formed with 20 ribs F', as shown in Fig. 8, to provide for a larger quantity of oil being lifted thereby to the axle-bearing; or said ribs may be dispensed with, and in lieu thereof a series of holes or recesses may be bored or formed in the walls 25 of the annular chamber of said collar.

L represents the lid for section B, which consists of a plate, l, pivoted or riveted at l' to section B. Said plate is formed with a boss, l'', having an opening, l', closed by a cap, 30 l', riveted or otherwise secured to boss l'', as shown at l'. Through said cap passes a rod or shank, M, which enters opening l', and is provided with a collar, m, and a spiral spring, N. To the end of shank M is secured a projection, m', having a recess, m'', which normally rests or abuts against plate L and passes around a lug, a, on section B. The tendency of spring N being in the direction of arrow x, it follows that the recessed end m'' is thereby 35 held in close impingement with lug a when the lid is closed on section B; but when said lid is designed to be opened, the end m'' is pushed or drawn in a direction opposite to that of arrow x and at the same time the lid L 40 is rotated, whereupon the end m'' is unlatched from lug a. Such movement is indicated in Figs. 11 and 12. The end m'' is represented as being semicircular in outline to fit around the correspondingly-shaped lug a; but it may 45 be of any other suitable configuration.

It will be noticed from the foregoing that my improved axle-box is completely closed at both ends, so that no dust can find its way therein. The revolving collar on the axle 55 supplies or feeds the oil to the journal-bearing, while the abutment of said collar against the packing or gasket prevents end-thrust of the axle; or, if such action should occur, its injurious effects are absorbed by said packing, 60 and thereby prevented from falling upon the axle-box, to break, strain, or cause undue wear of the same.

The gasket or packing may be formed of rubber, gutta-percha, asbestos, or other suitable fibrous or plastic substance.

What I claim is—

1. A car-axle box composed of an inner

and an outer section, the latter having a bottom, but no top, and its upper edge being substantially flush with the top of the inner section, as shown and described. 70

2. A car-axle box composed of two sections relatively removable from one another, the inner section being provided with an oil-well, a bearing for the axle, and having the lid of 75 the axle-box secured thereto, substantially as shown and described.

3. A car-axle box composed of sections B C, the section B having a bearing or seat, b', open ends b' b', seat b', and grooves b', and 80 the section C having flanges c', substantially as shown and described.

4. The combination, with a car-axle box composed of an inner and an outer section, of an axle having a collar which serves as a dust-shield, and an oiler for said box, substantially 85 as shown and described.

5. The combination, with a car-axle box composed of two sections, one within the other, each having a rear wall, of an axle having a 90 collar interposed between said rear walls for preventing end-thrust of the axle, substantially as shown and described.

6. The combination, with axle-box sections B and C, of axle E, provided with collar F and 95 interposed gasket or packing D, substantially as shown and described.

7. In a car-axle box, the combination of two sections forming the box, one section being within the other, and provided with a gasket 100 or packing abutting against a collar secured to the axle, substantially as shown and described.

8. The combination, in a car-axle box, of two sections composing said box, a gasket or packing-ring, an axle, and a collar secured thereto in impingement with said gasket, to serve as a dust-shield and an oiler for the journal, substantially as shown and described. 105

9. The pivoted or swinging lid L, having 110 boss l'', cap l', sliding bar M, with semicircular end m', correspondingly-shaped under-cut or notch m'', and spring N, substantially as shown and described.

10. The combination, with a car-axle box 115 having semicircular lug a, of the swinging lid L, having bar M, spring N, and semicircular end m', with correspondingly-shaped slot or recess m'', substantially as shown and described.

11. The section B, having open ends b b', bearing b', ribs or flanges b' b', seat b', and 120 grooves b', in combination with section C, having flanges or ribs c', the gasket or packing D, axle E, and collar F, substantially as shown and described.

12. The combination of sections B C, collar F, axle E, and hinged flap I, substantially 125 as shown and described.

13. A car-axle box composed of an inner and an outer section, and an oiling device located between the rear sides of said sections, for feeding oil onto the rear end of the journal-brass, substantially as shown and described. 130

14. A car-axle box composed of an inner and an outer section, each of which has a rear wall, between which is located a lubricator, and a gasket or packing interposed between said lubricator and the rear wall of the inner section, substantially as shown and described.

15. A car-axle box composed of two sections, one within the other, and each having a rear wall, and an interposed rotary disk to which serves as a dust-shield and a dust-excluder, substantially as shown and described.

16. The combination of two sections, B C, lid L, gasket or packing D, collar F, and axle E, substantially as shown and described.

In testimony whereof I affix my signature in presence of two witnesses.
